UNITED STATES PATENT OFFICE.

FRANK S. INGOLDSBY AND JOSEPH R. BOWLING, OF ST. LOUIS, MISSOURI,
ASSIGNORS TO THE INGOLDSBY AUTOMATIC CAR COMPANY, OF ST. LOUIS,
MISSOURI, A CORPORATION OF WEST VIRGINIA.

DUMP-CAR.

SPECIFICATION forming part of Letters Patent No. 744,201, dated November 17, 1903.

Application filed February 20, 1903. Serial No. 144,915. (No model.)

To all whom it may concern:

Be it known that we, FRANK S. INGOLDSBY and JOSEPH R. BOWLING, both citizens of the United States, residing at St. Louis, in the 5 State of Missouri, have invented certain new and useful Improvements in Dump-Cars, of which the following is a full, clear, and exact description, reference being had to the accompanying drawings.

10 The object of this invention is to produce a very light and strong dump-car which at the same time shall be very simple and cheap in construction.

15 The car which constitutes this invention is of what is known as the "Ingoldsby" type—that is, it has a central longitudinal beam to which there are hinged dumping-doors adapted to swing downward at their outer edges.

20 The car herein shown is particularly adaptable for the transportation of ore, though of course is not limited thereto.

25 The particular features of the present invention are the construction and arrangement of the central longitudinal beam, the stops for limiting the downward movement of the dumping-doors, the construction of those doors, particularly at their outer edges, and the coöperating arrangement at the lower edges of the car side, and finally the arrangement of the operating member for the locking-levers. All these features will be hereinafter more fully explained, and the essential combinations embodying the same set out in the claims.

30 The drawings clearly disclose this invention embodied in an ore-car.

Figure 1 is a plan, half top plan and half bottom plan. Fig. 2 is an elevation, half-outside and half-sectional. Fig. 3 is an end view, half-outside and half-sectional. Figs. 4 and 5 are vertical sections on the lines 4 4 and 5 5, respectively, of Fig. 2. Figs. 6 and 7 are details in horizontal section, being respectively on the lines 6 6 of Fig. 3 and 7 7 of Fig. 5. Figs. 8 and 9 are details of two forms of connecting-plates used.

45 The car, as shown, is made almost entirely of sheet metal and rolled forms. It has plate girder sides A A, composed of vertical metal plates which have riveted along their upper

and lower edges and intermediately the angle members a', a², and a³, respectively. The projection of the horizontal flanges of these members increases with the tendency of the side of the car to bow outwardly. Thus the 55 uppermost flange a' is the widest, the intermediate flange a³ the next narrower, and the bottom flange a² the narrowest.

Between the sides near the ends of the car are the inclined end floors B. These inclined 60 ends are flanged downwardly at their edges b and are there riveted to the plates A. The inclined ends are strengthened and braced by the angle-strips b', b², and b³, which extend across them on their under sides at their 65 upper edge, their lower edge, and intermediately, respectively.

The central longitudinal member of the car is designated C. As here shown, it carries substantially half the load. It includes a 70 ridge-plate inclining downwardly on opposite sides and extending from bolster to bolster, passing through the end floors B, which are connected to it through the downward flanges of the connecting-strips b⁴.

75 The ridge-plate of the central beam C is braced laterally at various points by composite stiffening members D beneath the beam. This composite stiffening member, as shown, is composed of the angle-strip d, bent according to the angle of the ridge-plate and riveted to it, the two connecting-straps d' d', riveted to the strip d and the ridge-plate, the tie angle-strip d², riveted near its ends to the connecting-straps d' d', and the connecting-plates 85 d³, riveted to the flanges of the angle-strips d and d². This make a light and at the same time strong triangular brace beneath the ridge-plate. To further stiffen the central beam, (but not necessarily essential to it, 90 though of utility in taking the shocks and strains due to buffing and tugging of the cars,) we provide a pair of outwardly-facing channels E E, which run through the car and have riveted to their webs inwardly-turned flanges 95 d⁵ on the inner edges of the plates d³. The longitudinal channels E are secured at their ends by angle-plates e to the end sills F of the car. They extend over the bolsters G of the car, which, as shown, consist of a pair of 100

outwardly-facing channel-beams extending across the car beneath the central beam and carrying the usual center bearing g and side bearings g' . The ridge-plate C is connected with the bolster by the angle connecting-pieces c , riveted to each of them.

- 5 The draw-head H occupies a sheet-metal frame H' , which abuts the outer side of the bolster and is secured to it. This frame is also secured to the channel-beams E and is supported from the end sill F by the depending brace K. The end sill is riveted and secured by the connecting-plates f to the extension-beams a^4 , connected to the car sides. On the inner sides of the bolsters are the plates L, connected to the bolsters and to the longitudinal channels E E. The bolster is thus bound to these channel-beams through the draft-plates H' and these backing-plates L.
- 10 20 At its outer ends the bolster is connected with the lower chord a^2 of the car side by connecting-plates g^3 .

The dumping-doors P consist of sheet-metal plates secured to floor-beams p beneath them. 25 These floor-beams extend inward between the straps d' of the triangular brace D, to which they are hinged by pins p' , projecting each way from the floor-beam. The floor-plates are turned upward at their inner edges p^2 to 30 make a tight joint with the lower edge of the ridge-plate C. At their outer edges p^3 the floor-plates extend beneath the lower edge of the side plate A and the lower chord a^2 a sufficient distance to make a tight joint therewith. 35 These doors are braced at their outer edges by the longitudinal angle-strip p^4 beneath the floor-beams and secured to the door by rivets passing through these floor-beams and other rivets through distance-blocks p^5 , located intermediate of the floor-beams. This effectively braces the outer edge of the dumping-door. When the car is in condition for loading, the doors P are held horizontally by the engagement with the outer ends of the floor-beams p of hooked levers Q, pivoted to the 40 sides of the car. The outer ends of the floor-beams are also hooked. These two sets of hooks have coöperating inclined bevels to draw the parts snugly into place. The pivoted hooks 45 Q are adapted to be concurrently operated by a bell-crank lever S, connected with the hooks by a link T. The lever S is normally retained in an elevated position by a locking-bar V, which lies beneath it, and is pivoted by a pin v to the guide-iron U. This bar V 50 may be locked by the pin V'. When this pin is removed, the locking-bar V will be turned aside and the lever S swung downward. This swings the hooks Q on their pivots to release the floor-beams p and allow the doors to drop. 55 To form a stop for the doors as they drop, preventing their passing inward far enough to discharge on the rail, we provide at certain points beneath the central beam stops 60 consisting of downward outwardly-inclined projections, as d^6 and d^8 . These projections are respectively extensions d^6 of the angle-

ties d^2 and additional members d^8 . Near the center of the car the adjacent extensions d^6 are connected by the cross-plate d^7 . At the 70 points where these extensions are we also extend downward the connecting-plate d^3 beneath the triangular brace proper, as indicated at d^4 , this extension-plate d^4 being riveted to the extensions d^6 and d^8 . Thus when 75 the door drops the plate P is beyond the edge of the extension-plate d^4 ; but the floor-beams p , which are out of alinement with these extension-plates, impinge at the door ends the stops d^6 and at the center the cross-plate d^7 . 80 This makes an effective bumper for the door, holding it in position where the load will be discharged clear of the rail, while at the same time the car may be shifted on the rail with the doors down, if desired. An inspection of 85 Fig. 3 will show this and will also show that though the door inclines outwardly in its lowest position the discharge-space is not contracted thereby, being greater than the horizontal distance between the lower edge of the 90 central beam and the side of the car. In order to allow the dumping-doors to be conveniently elevated, we provide at their outer edges loops or handholds p^6 , which may be taken hold of by the attendant and the door thereby raised. 95

The locking-levers Q are mounted on blocks a^5 , secured to the car sides. These levers extend through slots a^6 in the lower chords a^2 of the sides, as shown particularly in Fig. 6. This arrangement, as well as the projecting 100 flange a^8 above the levers, effectively protects them from injury. The slots through the lower chord a^2 are located in or very close to the neutral axis of the horizontal flange of that chord—that is, the line where the stress 105 in it changes from tension to compression—so that, practically speaking, they do not weaken the chord.

In operation after the car is loaded it is dumped by simply removing the pin V', turning aside the locking-bar V, and shoving downward the lever S. This swings the hooks Q to release the doors, and the latter drop by gravity, discharging the load. Thereafter the doors are raised by the attendant, who 110 takes hold of the handholds p^6 and raises the doors to a horizontal position and then by taking hold of the link T shifts the hooks Q sufficiently to hold the door, after which he moves the lever S home and locks it with the 115 locking-bar. The lever S is so proportioned that when it has been shoved downward to release the doors the short arm S' thereof stands in a substantially vertical position, so that when the attendant pulls on the link T 120 he has this arm S' in position of greatest leverage, making the operation easy and convenient. The lever S may be operated from the side of the car or, if desired, from the platform m , which extends across the end of 125 the car. This platform is also of use for operating the brake, which is indicated in the drawings by the hand-wheel and rod N, connecting-chain N', and equalizing-lever N². 130

We claim—

1. In a dump-car, a sheet-metal ridge-plate, a composite brace beneath the same secured to it and composed of an angle-strip riveted to the under side of the ridge-plate, a cross-strip beneath the angle-strip, and a connecting-strap near the corners of the ridge-plate riveted to both said cross-strip and said angle-strip. 5
- 10 2. In a dump-car, the combination of an inverted-V-shaped sheet-metal plate, a tie-strip extending crosswise of the plate beneath it, and a pair of bent straps, each having one arm riveted to the cross-strip and the other arm riveted to the plate. 15
- 15 3. The combination of an inverted-V-shaped plate, a triangular brace beneath the same consisting of a ridge member, a cross member, a pair of bent straps connecting said two members at their ends, and connecting-plates riveted to both said members. 20
- 25 4. The combination of a ridge-plate, a pair of channel members beneath the same, open triangular braces beneath the ridge-plate secured to it and extending around the channel members and connected to them. 25
- 30 5. The combination of a ridge-plate, a pair of outwardly-facing channel members beneath the same, cross-ties for the ridge-plate beneath the channel members, and connecting-plates riveted to the cross-ties and to the channel members. 30
- 35 6. The combination of a ridge-plate, a pair of outwardly-facing channel members beneath the same, cross-ties for the ridge-plate beneath the channel members, connecting-plates riveted to the cross-ties and to the channel members, and angle members riveted to the ridge-plate, said connecting-plates being 40 riveted to said angle members. 40
- 45 7. The combination of an inverted-V-shaped plate, a triangular brace beneath the same consisting of a ridge member, a cross member, a pair of bent straps connecting said two members at their ends, and connecting-plates riveted to both said members, and a pair of longitudinal channel members beneath the V-shaped plate, said connecting-plates being riveted to the webs of the channel members. 50
- 50 8. In a dump-car, the combination of a pair of bolsters, a ridge-plate extending from bolster to bolster, a pair of channel members beneath the ridge-plate also extending from bolster to bolster, said ridge-plate and channel members being secured together, and each being secured to the bolsters. 55
- 55 9. The combination of a pair of bolsters, a ridge-plate extending from bolster to bolster and secured to them, a pair of channel members beneath the ridge-plate extending from one end of the car to another, end sills to which said channel members are connected, said channel members being intermediately connected with the bolsters. 60
- 65 10. The combination of a pair of bolsters, a ridge-plate extending from bolster to bolster and secured to them, a pair of channel mem- bers beneath the ridge-plate extending from one end of the car to the other, end sills to which said channel members are connected, said channel members being intermediately connected with the bolsters. 65
- 70 11. In a dump-car, the combination of a plate, cross-braces beneath the same, a pair of bent straps connecting said cross-braces with the plate, and a dumping-door having a floor-beam and a hinge-pintle engaging said floor-beam and the inner sides of said straps. 75
- 75 12. In a dump-car, the combination of a plate, braces beneath it, bent straps connecting said braces with said plate, vertical connecting-plates riveted to said braces, dumping-doors, and hinge-pins therefor confined between said bent straps and said vertical connecting-plates. 80
- 80 13. In a dump-car, the combination of an inverted-V-shaped sheet-metal plate, a tie-strip extending crosswise of the plate beneath it, a pair of bent straps, each having one arm riveted to the cross-strip and the other arm riveted to the plate and dumping-doors hinged by pins held on the inner sides of said bent straps. 85
- 85 14. In a dump-car, the combination of a plate, ties extending crosswise of the plate beneath it, a pair of bent straps each having one arm riveted to the ties and the other arm riveted to the plate, and a dumping-door consisting of a sheet-metal plate and floor-beams beneath it, said beams extending between adjacent members of said bent straps. 90
- 90 15. In a dump-car, the combination of a plate, a pair of ties extending crosswise of the plate beneath it, a pair of bent straps each having one arm riveted to the ties and the other arm riveted to the plate, a dumping-door consisting of a sheet-metal plate with a floor-beam beneath it, said beam extending between adjacent members of said bent straps, a pin projecting each way from said floor-beam and making a hinge with said straps, 95 and plates serving both to brace said ties and confine said pins. 100
- 100 16. In a dump-car, the combination of a beam, braces therefor beneath it, downwardly and outwardly inclined projecting members supported by the beam, and a dumping-door adapted to swing downward, said members constituting bumpers for said door. 105
- 105 17. In a dump-car, the combination of a ridge-plate, triangular braces therefor beneath the plate riveted to it, dumping-doors pivoted to said braces, and downwardly-projecting outwardly-inclined members supported by said braces and forming stops for said doors. 110
- 110 18. In a dump-car, an inclined sheet-metal plate, a strengthening member therefor beneath the plate and riveted to it, said strengthening member including a down- 115
- 115 130

- wardly-extending cross-plate, a dumping-door pivoted to said strengthening member, and a strip riveted to said downwardly-extending plate and forming a stop for said door.
- 5 19. In a dump-car, a plate, a strengthening member beneath the same riveted to it, said strengthening member including a cross-strip, the end of said cross-strip being turned downward, and a dumping-door for which such downward extension forms a stop.
20. In a dump-car, in combination, a ridge-plate, strengthening members beneath the same and consisting of vertical plates, with angle-strips riveted to them, said strengthening members being riveted to the ridge-plate, downwardly-extending outwardly-inclining angle-strips riveted to said vertical plates, and dumping-doors for which said outwardly-extending angle-strips form stops.
21. In a dump-car, in combination, a dumping-door, a ridge-plate, a pair of strengthening members beneath and secured to the ridge-plate and consisting of vertical plates, angle-strips riveted to said plates and extending downwardly and outwardly, and straps connecting said angle-strips and forming bumpers for said door.
22. In a dump-car, a metal dumping-door having a longitudinal bracing-strip on its under side near its free edge, combined with bumpers to receive the impact of said door when it drops.
23. In a dump-car, a dumping-door consisting of a sheet-metal plate having floor-beams beneath it, a longitudinal bracing-strip on the under side of the door near its free edge beneath the floor-beams and riveted thereto, and bumpers against which said floor-beams are adapted to impinge when said door drops.
24. In a dump-car, the combination of a dumping-door consisting of a sheet-metal plate having floor-beams beneath it, a longitudinal bracing-strip on the under side of the door near its free edge and beneath the floor-beams, distance-blocks between the bracing-strip and sheet-metal plate, and rivets passing through said bracing-strip, distance-blocks and sheet-metal plate.
25. In a dump-car, the combination with a car side having a vertical plate with a horizontal flange at its lower edge, of a longitudinal beam, a door pivoted thereto and adapted to extend outward beneath the plate and flange of the car side, and means for forcing said door snugly against the lower edge of said plate and flange.
26. In a dump-car, the combination with a car side having a vertical plate, with a horizontal flange at its lower edge, of a longitudinal beam, a sheet-metal door having floor-beams on its under side, said floor-beams being pivoted at their inner ends to the longitudinal beam, said sheet-metal door and floor-beams extending outwardly beneath the vertical plate and horizontal flange of the car side, and means carried by the car side for engaging the floor-beams to force the door snugly against the lower edge of the flange and of said side.
27. The combination with a car side having a vertical plate and a flange at its lower edge, of a pivoted hook extending through an opening in said flange, a pivoted door having a floor-beam adapted to extend beneath said hook and be interlocked therewith.
28. The combination with a car side having a vertical plate and a flange at its lower edge, of a pivoted hook extending through an opening in said flange, a pivoted floor having a floor-beam adapted to extend beneath said hook and be interlocked therewith, the opening through the flange for the passage of said hook being substantially in the neutral axis of the flange.
29. In a dump-car, the combination of a longitudinal central beam, a pair of plate-girder sides having their lower chords in the form of angle-beams at the extreme lower edges of the sides, said angle-beams having outwardly-extending horizontal flanges, dumping-doors pivoted to the central beam and adapted to extend beneath the car sides and engage the same, and pivoted hooks carried by the car sides and extending through openings in the said horizontal flanges and adapted to engage the floor-beams carried by said dumping-doors.
30. In a dump-car, the combination with a car side and a central longitudinal beam, of a dumping-door pivoted to the beam and carrying projected floor-beams, hooks pivoted to the car side and adapted to engage said floor-beams, a longitudinally-movable link connecting said hooks, a bell-crank lever pivoted to the car side and having a short arm connected to said link and having the other arm extending toward the end of the car whereby the movement of the end of the lever in an approximately vertical path may cause the hooks to release the floor-beams.
31. A car having a sheet-metal side carrying a series of outwardly-projecting longitudinal flanges, the amount of projection of said flanges increasing from the bottom upward.
